UNITED STATES PATENT OFFICE

ELMER S. GROSS, OF HARRISBURG, PENNSYLVANIA, ASSIGNOR OF ONE-HALF TO
FRANK H. GREGORY, OF HARRISBURG, PENNSYLVANIA.

TANG-DRIVEN TOOL.

1,043,098.

Specification of Letters Patent. Patented Nov. 5, 1912.

Application filed October 6, 1911. Serial No. 653,283.

To all whom it may concern:

Be it known that I, ELMER S. GROSS, a citizen of the United States, and a resident of Harrisburg, in the county of Dauphin and State of Pennsylvania, have invented new and useful Improvements in Tang-Driven Tools, of which the following is a full, clear, and exact specification, such as will enable any one skilled in the art to understand and use the invention as herein described.

This invention relates to improvements in the tangs of tang-driven tools, and the sockets therefor, and it has for one of its objects the provision of a tool having a tang which consists of a plurality of wings adapted to be engaged by correspondingly-shaped abutments in either the spindle, or the chuck, or the driver-bushing and holder.

The invention has, furthermore, for its object, the peculiar organization or arrangement of such wings so that the tool can be entered into its socket only in certain positions.

Further objects of the invention will hereinafter appear and be particularly defined in the claims.

The invention has been clearly illustrated in the accompanying drawings in which similar characters denote similar parts, and in which:—

Figure 1 is a front view of a socket and a tool held therein in accordance with my invention; Fig. 2 is a horizontal section thereof on line 2—2 of Fig. 1; Fig. 3 is a side view of the holder, partly broken away, substantially on line 3—3 of Fig. 1; Fig. 4 is a front view of the tool shank, *per se*, and Fig. 5 is a top view thereof.

Referring to the drawings, 10 denotes the body of the tool, as for instance, a twist drill having a tapered shank 11, the upper end of which has a tang comprising in the present instance four wings, 12^a, 12^b, 12^c, and 12^d. Of these, the wings 12^a, 12^b are in diametrical alinement in exactly the same manner as the ordinary tang in common use, while the other wings, 12^c, and 12^d, constitute side projections of the straight tang and are offset centrally (see Fig. 5,) and are consequently unaligned. The several wings are formed on the round-taper shank by a pair of milling cutters (as indicated in dotted lines in Fig. 5,) to such an extent longitudinally of the shank that the cut-depth remains uniform from the top downward to about the line *a*.

In order to accommodate or provide proper driving engagement between the 60 tang-wings and the holder H, the latter is bored out round far enough, to substantially the extent shown in Fig. 3, while the upper portion of the holder body is only slotted crosswise to correspond to the positions and sizes of the tang-wings, as at 13^a, 13^b, 13^c, and 13^d, respectively. Hence there are established four abutments on the holder, as 14^a, 14^b, 14^c, 14^d, which drive the respective wings.

From the foregoing it will be seen that a tool having the common tang may be used in my improved holder, which, of course, is also adapted to receive a tool provided with my improved tang. Furthermore, that the ordinary socket needs only (in addition to the slot for the drifting key,) a pair of cross slots to adapt it for the reception of my improved tang tool. Also, that the new tang-drive is practically twice as powerful as the single-tang construction, without interfering in the least with the regular standard taper of the shank.

By reason of the fact that the side wings are "off center" there is gained the advantage of having the driving faces of the abutments near the line of force in which the tool is rotated. Another advantage is that in case the ordinary flat-tang drill is used it will be driven by the heavier abutments of the socket or holder (see Fig. 2). It will also be noted that an ordinary flat-tang tool cannot be placed into the socket into the cross-slots because the latter are out of register; therefore it must be placed into the regular slots, which are high enough to permit the insertion of a drifting key to remove the tool.

Changes may be made in the construction of the tang, especially as to the number and shape of the wings, without departing from the spirit of the invention as set forth in the appended claims.

I claim:—

1. A tool or socket provided with a tapered shank, having its upper end cut to form wings extending longitudinally of the shank and offset relatively to each other diametrically of the shank.

2. A tool or socket provided with a tapered shank having a tang extending diametrically across the shank, and having wings extending to opposite sides thereof and offset relatively to each other diametrically of the shank.

3. The combination with a tool having a shank provided with a tang comprising wings, and offset relatively to each other diametrically of the shank of a socket having slots extending through the body thereof and adapted to receive said wings respectively.

4. The combination with a tool having a shank provided with a tang comprising

wings and offset relatively to each other diametrically of the shank, of a socket having slots extending through the body thereof and adapted to receive said wings respectively, one of said slots extending diametrically across the body and having a greater length than the other slots, and adapted to receive a drifting key.

In testimony whereof I have signed this specification in the presence of two subscribing witnesses.

ELMER S. GROSS.
